Nelson W. Howard

UNITED STATES PATENT OFFICE.

WILFRID THOMAS MINETT, OF LEICESTER, ENGLAND, ASSIGNOR TO UNITED SHOE MACHINERY CORPORATION, OF PATERSON, NEW JERSEY, A CORPORATION OF NEW JERSEY.

HEEL-ATTACHING MACHINE.

Application filed July 2, 1924. Serial No. 723,687.

This invention relates to the attachment of the heels of shoes, and is particularly concerned with the attaching, from the inside of shoes, of such relatively high and 5 heavily curved heels as those of the Louis type.

In attaching heels of this character, it has been usual, in applying pressure to retain them upon the heel-seats of the shoes 10 for nailing, to employ an abutment for the tread-surface and an abutment for the rear of the heel, as shown, for example, in United States Patent No. 1,269,654, Standish, June 18, 1918. Here, the rear abutment is mounted 15 upon the same head that carries the tread-abutment, this arrangement giving the necessary clearance for easy positioning of the shoe and heel and subsequent removal of the heeled shoe. While such a construction 20 is satisfactorily employed when attaching heels by short nails, which do not require heavy driving pressure, nor, consequently, great resistance to displacement of the heels, other types of heels call for the use of 25 longer attaching nails and heavier pressure to be exerted upon the tread-face, and the customary devices may not hold such heels securely. Accordingly, an object of the present invention is to provide a heel-holding 30 device, which, while giving ample clearance for the positioning and removal of the work, is adapted to retain a heel, and especially the rear portion of a heel having a considerable slope, rigidly against such forces as 35 may be exerted in driving a number of comparatively long nails. This object I attain by the provision, in apparatus for attaching heels, of means for applying pressure to different portions of such heels, as 40 to the tread-surface and to the rear surface, their being a member connecting one of said pressure-applying means to the other, to cause its movement, and a member connecting the pressure-applying means thus moved 45 to a relatively fixed point, to modify its movement. The pressure-applying means the movement of which is thus modified may be a rear abutment movable through a link by the tread-abutment, and the movement- 50 modifying member, which may be a link connected to the rear abutment and to the machine frame, may act as a brace against the pressure of the tread-abutment, and may also cause the rear abutment to be so posi-

tioned as to give the desired clearance for 55 the handling of the work.

The above and other objects of the invention will become apparent from a consideration of the following description, given by way of example, of a preferred construction 60 embodying the invention and illustrated by the accompanying drawing, in which

Fig. 1 shows said construction in side elevation, parts being broken away;

Fig. 2 is a horizontal sectional detail on 65 the line 2—2 of Fig. 1; and

Fig. 3 is a perspective view of the bracket to which the vertical abutment-link is pivoted.

At 10 appears a portion of the column or 70 frame of such a heel-attaching machine as that disclosed in United States Patent No. 1,195,134, Gouldbourn, August 15, 1916, this frame supporting a jack 12, through which the attaching nails are driven, and also having 75 mounted to reciprocate upon it a pressure-head 14. The head carries a pressure member or abutment 16, having its lower face formed and arranged to contact with the tread-surface of a heel H applied to the heel-seat of a jacked shoe S. The abutment 16 may be adjusted from front to rear of the machine upon the head by a screw 18, and may also be moved angularly in the 80 same general direction by a screw 20. These 85 adjustments permit the abutment 16 to be positioned for proper contact with heels of different form.

On account of the angle at which the tread-surfaces of Louis and like heels lie 90 with relation to the heel-seats, as is well illustrated in Fig. 1 of the drawing, pressure applied by the abutment 16 results in a substantially horizontal component toward the rear of the machine, this tending to displace the heel from the shoe. This must be resisted in clamping such heels for nailing. It is also desirable to hold the extreme rear portion of the heel firmly in contact with the heel-seat, to insure a tight 100 crease when the attaching nails are driven. For these purposes, there is arranged for engagement with what is normally the upper and rear curved portion of the heel H an abutment 22, pivoted upon a carrier 24, this 105 pivotal mounting allowing the abutment to adjust itself to different inclinations of this heel-surface. To actuate the rear abut-

ment, so it may exert its pressure simultaneously with that of the tread-abutment, it is movable under the control of the latter by a connection, preferably consisting of a link 26 pivoted both to the carrier 24 and to a divided bracket 28 projecting rearwardly from the pressure-head. This movement of the rear abutment is modified to change its direction of travel under the influence 10 of the tread pressure member, and it is braced during the final application of pressure and the nailing operation by a second connection, independent of that to the tread-abutment. This is shown as consisting of 15 a link 30 joined to the carrier and pivoted to some such relatively fixed point as a bracket 32 mounted upon the column 10 at the rear of the jack.

The shoe S having been placed upon the 20 jack and the heel H applied to the heel-seat, the head 14 descends vertically in the operation of the machine, carrying the abutment 16 in a straight path, to bring its end face into clamping engagement with the 25 tread-surface of the heel. Prior to starting the machine in operation and during the application of the work to the jack, the rear abutment has been held elevated by the link 26, it occupying the position illustrated in dotted lines in Fig. 1 of the drawing. This is well to the rear under the influence of the link 30 which, as the head rises, draws the carrier away from the jack. The resulting position of the rear abutment 30 so removes it from the jack that interference in the application of the shoe and heel is avoided. During the downward movement of the tread-abutment, the link 26 lowers the abutment 22, while the link 30, 35 turning upon the frame, carries said abutment forward transversely of the path of the tread-abutment into engagement with the rear of the heel. When this pressure-applying movement is completed, the link 40 45 50 55 60 occupies a substantially horizontal position, so that the horizontal component of the applied force previously referred to is directly resisted by this connection to the frame, with practically no stress tending to disengage the abutment from the work. The nails having been driven through the heel-seat of the shoe into the heel, the head 14 rises, and as the tread-abutment is elevated thereby, the rear abutment is also 65 70 75 80 85 90 95 100 105 110 115 120 125 130 lifted from the heel and carried back clear of the jack, ready for the removal of the work and the application of the succeeding shoe and heel.

To adapt the member 22 for effective 60 65 70 75 80 85 90 95 100 105 110 115 120 125 130 operation with heels of different forms or dimensions, means are provided for varying both the point to which it moves downwardly and also the extent of its travel toward the jack. For this purpose, the link 26 is swiveled at 34 to the carrier 24, and is

threaded at 36 through a block 38, this block having opposite lateral projections or trunnion-pins 40, 40 supporting the link in the divided bracket 28 on the pressure-head. By turning the link 26 by an enlargement 70 or thumb-piece at its upper extremity, the pressure-applying position of the abutment member 22 may be raised or lowered. The link 30 has, surrounding its inner extremity, an externally threaded sleeve 42 turning upon the link but being held against longitudinal movement. A pivot-pin 44, which turns in the bracket 32 upon the frame, has a threaded opening, which the sleeve engages. Rotating the sleeve will draw the 75 abutment member 22 in or out, thus adjusting the pressure-applying position of the abutment horizontally. To more precisely determine the angle at which the link 30 lies when resisting the nailing pressure, so that its bracing action may be most effective, the bracket 32 is formed upon a slide 46 movable vertically upon the column and clamped by a screw 48.

For some classes of work, it may be desired not to employ the rear abutment. To permit it to easily be put out of action, the pivotal connection to the bracket 28 is made readily detachable. For this purpose, the pins 40 are surrounded by flanged sleeves 50, the outer diameter of which is such that they fit alined perforations 52, 52 in the bracket 28. The sleeves are held in engagement with the bracket-perforations, when the rear abutment is to be employed, by spring-latches 54, 54, which enter annular grooves 56, 56 in the pins. Through the front wall of the bracket, from the perforations 52, 52, are contracted openings 58, 58, which are too narrow to permit the 100 sleeves to pass. When the operator wishes to detach the link from the bracket, the latches are raised from the grooves 56, and the sleeves drawn out until they are stopped by the latches entering grooves 60, 60. The 105 sleeves are now wholly outside the bracket, and the pins are sufficiently small to pass through the openings 58. Thus freed from the tread pressure member, the link-system may be left suspended inactive upon the 110 pivot-pin 44.

Having described my invention, what I claim as new and desire to secure by Letters Patent of the United States is:

1. In a heel-attaching machine, a plurality of movable pressure-applying means for contact with a heel to be attached, a member for connecting one of said pressure-applying means to the other to cause its movement, and a member connecting the pressure-applying means thus moved to a relatively fixed point to modify its movement.

2. In a heel-attaching machine, a plurality of movable abutments for contact with a heel to be attached, a link joining one of said

abutments to another, and a link joining such abutment to a relatively fixed point.

3. In a heel-attaching machine, a tread-abutment for a heel to be attached, a movable rear abutment for the heel, and connections for controlling the movement of the rear abutment, said connections including a link pivotally connected to the rear abutment and tread-abutment.

19 4. In a heel-attaching machine, a tread-abutment for a heel to be attached, a movable rear abutment for the heel, connections for controlling the movement of the rear abutment, said connections including a link joining the rear abutment and tread-abutment, and means arranged to vary the effective length of the link.

5. In a heel-attaching machine, a frame, a movable rear abutment for a heel, and connections for controlling the movement of the abutment, said connections including a link pivoted to such abutment and the frame.

25 6. In a heel-attaching machine, a frame, a tread-abutment for a heel to be attached movable upon the frame, a movable rear abutment for the heel, and links connecting the rear abutment with the tread-abutment and with the frame.

30 7. In a heel-attaching machine, a frame, a tread-abutment for a heel to be attached movable upon the frame, a movable rear abutment for the heel, links connecting the rear abutment with the tread-abutment and with the frame, and means arranged to vary the effective length of the links.

35 8. In a heel-attaching machine, a frame, a pressure member mounted to reciprocate thereon, a second pressure member movable under the influence of the associated pressure member, and movement-modifying connections between the frame and said second

pressure member, the point of attachment of the connections to the frame being normally fixed against movement in the operation of the machine but variable in position.

45 9. In a heel-attaching machine, a frame, a tread-abutment for a heel to be attached movable upon the frame, a rear abutment movable under the influence of the tread-abutment, a bracket adjustable upon the frame, and a link connecting the bracket and rear abutment.

50 10. In a heel-attaching machine, a movable heel-abutment, and a pivotally connected link for controlling the movement of the abutment, such pivotal connections having openings of different dimensions and there being members cooperating with the respective openings and arranged to retain or release the connections.

55 11. In a heel-attaching machine, a movable heel-abutment, movement-controlling connections for the abutment including a bracket, a link pivoted thereto, one of said pivoted members having openings of different diameters, and a pin carried by the other member and provided with portions respectively co-operating with such openings for its retention and release.

60 65 12. In a heel-attaching machine, a movable tread-abutment having a perforation with a contracted opening through its surrounding wall, a movable rear abutment, a link pivoted to the rear abutment, a pin carried by the link and being of a diameter to pass through the opening in the tread-abutment, and a sleeve movable upon the pin and arranged to fit the perforation of the tread-abutment.

70 75 80 In testimony whereof I have signed my name to this specification.

WILFRID THOMAS MINETT.
